AMUSEMENT DEVICE

Moses Goldman, Brooklyn, N. Y.

Application October 27, 1937, Serial No. 171,332

6 Claims. (Cl. 273—97)

This invention relates broadly to amusement devices and toys and more particularly, to devices of this character, comprising a ring or hoop attached to a rod. The dual object of the game is firstly to catch or impale the ring upon or with the rod through keenness of eye and, secondly, to catch the ring upon repose arms after it has been so caught or impaled.

It is an object of the present invention to provide a game comprising a ring attached to a rod which shall provide amusement and entertainment and a mild form of athletic activity or bodily exercise either for individuals or for groups of individuals.

It is another object of the present invention to provide a structure of the type indicated wherein means are included for retaining the hoop upon repose arms.

It is a feature of the present invention that means are provided to substantially minimize snagging or knotting of the cord whereby the ring is attached to the rod.

It is a further feature of the device according to the present invention that a guard is provided to protect the hand of the player against inadvertent striking with the ring during playing of the game.

It is another feature of the device according to the present invention that means are provided for retaining the ring at all times in substantially centered condition relative to the string whereby it is attached to the rod.

The invention will be fully and comprehensively understood from a consideration of the following detailed description when read in connection with the accompanying drawing which forms part of the application.

In the drawing:

Fig. 1 is a side view of the preferred embodiment of the present invention; and

Fig. 2 is a top plan view of the device illustrated in Fig. 1 with the string broken away for clearness.

Regarding certain of its broader aspects the present invention comprises an amusement device or game consisting of a ring, a spear associated with said ring and repose arms mounted on said spear. In playing the game, two objects are had in mind: first, to catch or impale the ring upon the rod or spear and, secondly, to cause the ring to rest upon the repose arms hereinafter referred to as guard members. Substantial skill is required in playing the game in order to correctly gauge the thrust of the rod, whereby the ring is

positioned directly upon the repose arms without conflicting with the rod.

In the preferred embodiment of the present invention herein illustrated, a rod 10 is substantially fixedly secured in a cylindrical handle 5 member 11 and attached at the free end to a ring 12 by means including an elastic string 13 attached to the midpoint of a cord 14, the ends of which are freely held in openings 15 of the ring. It is preferred that the cord 14 be retained 10 in the openings 15 by forming a knot on the end of the cord whereby rotative movement of the ring within the cord around the ring is freely permitted. A guard supporting member 16 is substantially fixedly secured on the handle 11 15 adjacent the place of attachment of said handle to said rod by means, for example, by the connecting members 17.

In the preferred embodiment of the present invention, the member 16 is an annulus. The member 16 carries a plurality of guard members 20 bent in a modified V-shape, substantially as shown, which carry on their free end an annular member 18, the latter being disposed concentrically relative to the member 10. 25

Referring to Fig. 1, it will be noted that the ring 12 is shown in phantom in position within the members 20. The members 20 are bent inwardly at the place generally designated at 19, whereby the ring 12 is substantially prevented from springing outwardly from its rest position during the playing of the game. It will be noted that in the preferred embodiment of the present invention, the V-shaped members 20 are associated with the annular members 16 and 18 by means including nuts and bolts 21, but it will be, of course, apparent to those skilled in the art that other means of attachment may be employed if desired. 35

In playing the game as hereinbefore referred to, the individual or groups of individuals propel the ring 12 in a manner whereby the elastic string 13 is stretched to a substantial degree and when said ring is propelled in this manner, the rod 10 is thrust forwardly or upwardly to cause to spear the ring and to cause the same to repose within the arms or guard members 20, substantially as shown in phantom in Fig. 1. It will be readily understood that continued propelling of 45 the ring member and thrusting of the rod will be a stimulating exercise and at the same time test the keenness of the eye in causing the ring to be reposed within the guard members. There is therefore provided a coordination of the eye 50

with the body movement similar to that existing in the well-known fencing game.

In the event that several persons play the game simultaneously, each is provided with a device and the first one to place the ring within the guard or the individual who succeeds in positioning the ring within the guard the highest number of times during a predetermined number of manipulations, as hereinabove referred to, is declared the winner.

It is also to be understood that the device tends to train the eye to become keen and sharp due to watching and following the ring with the eye in its projection or flight from the rod after it has been propelled into space. The distance of projection or flight of the ring into space, to a large measure depends upon the force used by the operator and the elasticity of the cord 13. The player will also desire to correctly time the thrust of the rod 13 through the ring in a skillful manner whereby the ring will not touch the rod in its return flight, thereby traveling near the same and finally reposing on the arms 20.

It will be noted that the projecting portions 19 of the V-shaped guard member substantially tend to prevent the ring from falling out once it has been placed within the guard. It will further be noted that the guard fully protects the hands of the player whereby the ring is prevented from striking the operator's hands.

It is to be understood that this improvement is capable of extended application and is not confined to the exact showing of the drawing nor to the precise construction described and, therefore, such changes and modifications may be made therein as do not affect the spirit of the invention, nor exceed the scope thereof as expressed in the appended claims.

What I claim is:

40 1. An amusement device of the type described comprising a rod, a handle carried on one end of said rod, a ring, means for associating said ring with the free end of said rod, guard means for protecting the hand of the user and for receiving and holding said ring during the use of the device, said guard means including an annulus, means for supporting said annulus substantially concentrically and in a plane substantially perpendicular to said rod, said means comprising a plurality of substantially V-shaped members, one of the free ends of each V-shaped member being associated with the rod and the other end with the annulus, said V-shaped members extending over the handle whereby to protect the hand of the user.

55 2. An amusement device of the type described comprising a rod, a handle carried on one end of said rod, a ring, means for associating said ring with the free end of said rod, guard means for protecting the hand of the user and for receiving and holding said ring during the use of the device, said guard means including an annulus, means for supporting said annulus substantially concentrically and in a plane substantially perpendicular to said rod, said means comprising a plurality of substantially V-shaped members, one of the free ends of each V-shaped member being associated with the rod and the other end with the annulus, said V-shaped members extending over the handle whereby to protect the hand of the user, and being provided with bent-over portions in the sides thereof adapted to removably hold said ring during use of the device.

70 3. An amusement device of the type described

comprising a rod, a handle carried on one end of said rod, a ring, means for associating said ring with the free end of said rod, guard means for protecting the hand of the user and for receiving and holding said ring during the use of the device, said guard means including an annulus greater in internal diameter than the external diameter of said ring, means for supporting said annulus substantially concentrically and in a plane substantially perpendicular to said rod, said means comprising a plurality of substantially V-shaped members, one of the free ends of each V-shaped member being associated with the rod and the other end with the annulus, said V-shaped members extending over the handle whereby to protect the hand of the user, and being provided with bent-over portions in the sides thereof adapted to removably hold said ring during use of the device.

4. An amusement device of the type described comprising a rod, a handle carried on one end of said rod, a ring, means for associating said ring with the free end of said rod, said means comprising a relatively short length of substantially inelastic string rotatably and freely held at the ends in openings formed diametrically on the peripheral portion of said ring and a relatively long length of substantially elastic string attached at one end to the free end of said rod and at the other end to the middle portion of said substantially inelastic string, guard means for protecting the hand of the user and for receiving and holding said ring during the use of the device, said guard means including an annulus greater in internal diameter than the external diameter of said ring, means for supporting said annulus substantially concentrically and in a plane substantially perpendicular to said rod, said means comprising a plurality of substantially V-shaped members, one of the free ends of each V-shaped member being associated with the rod and the other end with the annulus, said V-shaped members extending over the handle whereby to protect the hand of the user, and being provided with bent-over portions in the sides thereof adapted to removably hold said ring during use of the device.

5. An amusement device of the type described comprising a rod, a handle carried on one end of said rod, a ring, means for associating said ring with the free end of said rod, said means comprising a relatively short length of substantially inelastic string rotatably and freely held at the ends in openings formed diametrically on the peripheral portion of said ring, and a relatively long length of substantially elastic string attached at one end to the free end of said rod and at the other end to the middle portion of said substantially inelastic string, guard means for protecting the hand of the user and for receiving and holding said ring during the use of the device, said guard means comprising an annulus greater in internal diameter than the external diameter of said ring, a second annulus lesser in external diameter than the internal diameter of said ring, means for supporting said second annulus upon said rod adjacent the place where handle and rod are associated, means for supporting the other annulus substantially concentrically and in a plane substantially perpendicular to said rod, said means comprising a plurality of substantially V-shaped members, one of the free ends of each V-shaped member being associated with the second annulus and the other end with the other annulus, said V-shaped mem-

bers extending over the handle whereby to protect the hand of the user and being provided with bent-in portions in the sides thereof adapted to removably hold said ring during use of the device.

5. An amusement device of the type described comprising a rod, a handle carried on said rod, a ring, means for associating said ring with the

free end of said rod, guard means for protecting the hand of the user, said guard means adapted to removably hold the ring during the use of the device, and an annulus, positioned concentrically of said rod, carried by and forming part 5 of said guard means.

MOSES GOLDMAN.
